High-frequency antenna arrangement and method of
attenuating antenna loop noise, which consists
of two side-purified half-circumferential annular
windings on a loop, a central coupling coil and
a central connection to the loop, the two side-purified
windings being connected in series and having
a common connection to the central connection.

bottom side to shield the loop from the field of
the antenna. The side-purified half-circumferential
windings are connected in series and have a
common connection to the central connection. The
central connection is connected to the loop.

LOOP ANTENNA

Walter Berndt, Berlin, Germany, assignor to
Telefunken Gesellschaft für Drahtlose Tele-
graphie m. b. H., Berlin, Germany, a corpora-
tion of Germany

Application November 11, 1937, Serial No. 173,992
In Germany October 9, 1936

5 Claims. (Cl. 250—33)

This invention relates to a frame or loop antenna arrangement possessing only a small antenna effect.

It is known in the art that the direction diagrams or characteristics of loops or frames correspond to the calculated values only when it is possible to eliminate the antenna effect of the loop. Several ways and means have been disclosed in the earlier art to this end. The loop and the input circuit may be built symmetrically. The loop may be shielded electrically; the leads brought to the loop may be grounded through differential condensers, while the antenna effect finally may be compensated by an auxiliary antenna. Yet, in spite of all these steps an appreciable antenna effect will be found to be present, and it will always be compensated by the last-named means, namely, an auxiliary antenna. The requisite auxiliary antenna must possess a certain effective minimum size if its action is to be attainable in an adequate measure. However, it is often undesirable or inconvenient to use a large auxiliary antenna. For this reason it is desirable to design a loop antenna having inherently a low antenna effect.

The antenna effect of a loop of known construction is essentially due to capacitive dissymmetries to ground or casing of the two halves thereof. Another part of the antenna effect is due to the leads brought to the loop which, in most cases, are coupled with a circuit presenting a dissymmetric relation to ground.

Referring, now, to the drawing, Fig. 1 shows one form of my invention, while Figs. 2 and 3 show modifications thereof.

According to this invention, therefore, a loop is used which is not furnished with any direct supply leads or downleads and which consists of one or several turns L closed upon themselves. The connection with the receiver apparatus, as shown in Fig. 1, is established by means of a coil W annularly surrounding the turn or the turns of the loop. However, also two symmetrically mounted coils W, W may be employed as shown in Fig. 2. By means of static shielding of the annular coil or coils as shown in more detail in Figure 3, and connection with ground of the shielding means or with the casing R, the antenna effect may be cut down to a very low value.

A further reduction in the antenna effect is attainable by grounding the loop antenna L or connecting it with the casing R in a symmetrical manner. The grounding point of the loop turns will then be symmetrical to the annular coils (Fig. 2) or to the annular coil (Fig. 3).

The annular coils are included suitably in a tuned circuit which acts upon the grid of a tube (Fig. 2). If as close a coupling as possible is to be insured between the loop and the grid circuit, then the core of the annular coil may consist of iron or of a material containing low-loss iron K, as shown in Fig. 3.

By the use of two similar annular coils which are placed upon both sides of the grounding point of the loop, the loop arrangement is made of symmetric construction.

If the loop antenna is used for picking up a wide wave band, then it will be expedient to provide the annular coil with several convolutions which are tapped or reversed, it being understood, of course, that for each wave band distinct annular coils could be employed.

To obtain special directional effects the loop antenna of this invention which inheres no antenna effect at all or only a very small one, could be combined with one or several like or similar antennae; and the same could then be used either for reception or for transmission.

Referring to Fig. 3, R denotes the loop casing which acts also as a shield for the convolutions L and W the winding while S indicates a shield for the winding W. By the ground terminal indicated at E, the convolutions of the loop are earthed symmetrically in reference to the annular coil.

I claim:

1. Loop antenna comprising convolutions, said convolutions being closed upon themselves to form a closed circuit, means for coupling said loop to a receiver comprising coils annularly surrounding the loop convolutions and means for shielding said loop convolutions including a casing surrounding said convolutions and connected to the convolutions at the center of the portion surrounded by said coupling means.

2. A loop antenna comprising one or more convolutions said loop convolutions being closed upon themselves to form a closed circuit, means for coupling said loop to a receiver comprising a coil annularly surrounding the loop convolutions and means for electrostatically shielding said coil surrounding said coil and connected to ground at a point intermediate the ends thereof.

3. Loop antenna comprising convolutions, said convolutions being closed upon themselves to form a closed circuit, means for coupling said loop to a receiver comprising a coil annularly surrounding the loop convolutions and means for shielding said loop convolutions including a casing surrounding said convolutions and connected to ground.

to the convolutions at the center of the portion surrounded by said coupling means.

4. Loop antenna comprising a convolution, said convolution being closed upon itself, to form a closed circuit, means for coupling said loop to a receiver comprising coils annularly surrounding the loop convolution and means for shielding said loop convolution including a casing surrounding said convolution and connected to the convolution at the center of the portion surrounded by said coupling means.
5. Loop antenna comprising a convolution, said convolution being closed upon itself, to form a closed circuit, means for coupling said loop to a receiver comprising coils annularly surrounding the loop convolution and means for shielding said loop convolution including a casing surrounding said convolution and connected to the convolution at the center of the portion surrounded by said coupling means.
